EXPANSION JOINT

Antonio Fabbro, Tampa, Fla.

Application November 4, 1937, Serial No. 172,832

3 Claims. (Cl. 72—19)

This invention relates generally to concrete surfacing structures such as roads, pavements, floors, walls and the like; and more particularly to metallic expansion joints used to divide such structures into sections or slabs of predetermined dimensions.

It is well known that concrete roads or similar surfacing structures will, on account of contraction and expansion with changes of temperature and on account of the heaving and sinking of the ground or sub-beds, crack or divide along irregular lines and at irregular intervals when the road is built solid. The irregular breaking of the concrete is not only unsightly but it frequently results in the disintegration of the road to a very marked degree due to the breaking of the concrete along such cracks. This makes the maintenance cost of the roads or surfacing structure excessive and also materially shortens the life of such structure.

The main object of the present invention, therefore, is to provide a metallic insert forming an expansion joint between adjacent edges of the aforesaid sections or slabs to permit the slabs or sections to expand and contract without causing irregular cracks or breaks to appear upon the surface thereof.

A further object of the invention is to provide an expansion joint of the character referred to which can be readily adapted to support a dividing strip in position to form a straight edge or leveling of the surfaces of a second surface applied to a coarser sub-base or sub-surface.

Another object of the invention is to provide a joint of the character referred to which can be applied to vertical walls for the purpose of securing slabs or similar sections of concrete as a cover for said vertical walls.

Other objects of the invention will be apparent as the detailed description thereof proceeds.

In the drawing:

Figure 1 is a broken elevation of a system of concrete slabs supported by the expansion joint embodying the present invention and applied to a wooden vertical structure;

Figure 2 is a broken vertical section, to an enlarged scale, taken on the line 2—2 of Figure 1;

Figure 3 is a perspective view of a slab such as is shown in Figures 1 and 2, and provided with a part of the expansion joint referred to;

Figure 4 is a perspective view of a U-shaped cover adapted to be applied to the expansion joint to form a finish for the sections outlined by the various slabs in the surfacing structure;

Figure 5 is a broken vertical section through an expansion joint used as a base support for a straight-edged dividing strip employed when a finished surface is applied to a lower sub-surface or sub-base; and

Figure 6 is a bottom plan of a slab of concrete with the expansion joint members in the form of a panel secured thereto.

Referring to the drawing, in which similar parts are designated by like numerals:

The expansion joint illustrated in Figures 1, 2, 3, 4 and 6 is adapted to be suitably secured, during the pouring operation, to concrete slab 6. The joint proper comprises a primary part 7 formed of a strip of copper or other suitable rust-resistant material. This strip is bent first to form a flange 8 extending at right angles from a body portion 9 which is return-bent to form a flange 10 substantially parallel to the body portion 9. The flange 10 is spaced apart from the body portion 9 a sufficient distance to receive between them a plate 11 formed from a strip of copper or other similar sheet material constituting the secondary part 12 of the joint. The secondary part 12 comprises a flange 13 extending at right angles to an intermediate body part 14 which is return-bent to form a plate 15 connected at its lower end, as by bending the sheet 12, to the plate 11.

The flanges 8 and 13 as mounted on the supporting structure are intended to lie substantially in the same plane; and the parts 14, 15 and 11 of the secondary part of the expansion joint are separated from each other sufficiently to permit the adjacent slab 6 to move toward and from each other without undue strain. When the adjacent flanges are assembled on the supporting structure the space between the members 15 and 10 of the completed joint is intended to be filled with tar, macadam or other plastic material to seal the joint. When the sealing material is positioned in said space, the joint may be completed by applying thereto the U-shaped strip 16 which forms a finished edge for the expansion joint and defines the boundary of the various slabs in the finished structure.

To secure the slabs to a vertical wall or to the studs 17 thereof, one of the flanges of the joint, as for example the flange 13 shown in Figure 2, has a narrow clamping plate 18 connected thereto. This clamping plate 18 is provided with an aperture 19 to receive a nail or other securing means 20 at the end extending beyond the back parts of the joint. The other end of the clamping plate 18 is return-bent to form a flange 21.

embracing the flange 13 of the secondary part of the expansion joint. In this manner the hook formed by the return bend on the end of the clamping plate 18 forms a support for the upper edge of the slab 6 to which it is connected. As shown in Figure 4, the U-shaped cover 16 for the expansion joint must be provided with a slot 22 to receive the end of another cover extending from the adjacent and superposed slab.

10 The space 23 between the members 10 and 15 of the expansion joint is adapted to receive, as a substitute for the cover 16, a slotted cover 24. This cover 24 comprises a sheet of copper or other similar material bent to form two outer flanges 25 and 26 to engage the outer surfaces 15 of the expansion joint. The sheet forming the cover 24 is bent between its ends to form a recessed member 27 which extends into the recess 23 and is itself shaped to form a recess 28 in 20 which is seated a straight-edged strip 29.

15 The form of the invention shown in Figure 5 is designed for use in applying a second concrete surface 30 to a lower and coarser sub-base 31. The strips 29 may be of any suitable width, depending upon the desired depth of the finished 25 surface material 30; and form a small finished joint which not only defines the outline of the slabs of the surface, but also indicates the location of the expansion joint in the lower sub-base.

20 30 The elements of the joint shown in Figure 5 are substantially the same as those shown in Figures 2 and 3, except that a base member 32 of copper or similar sheet material is substituted for the clamping member 18. This member 32 comprises a flat base bent over at its opposite ends 35 to form flanges 33 and 34 embracing the flanges 8 and 13 of the expansion joint proper.

As shown in Figure 6, the primary and secondary parts of the metallic expansion joint may 40 be stamped from a single sheet of metal so that

the flanges 8 and 13 form a rectangular panel 5 suitably apertured to receive the ends of the reinforcing rods or wires R. On each slab, the primary part of the expansion joint extends along the remaining adjacent edges. Obviously, this construction enables the blocks to be made exactly alike, and permits their assembly with their vertical joints properly staggered or broken.

The invention is not to be considered as limited 10 to the specific details of construction described as shown, nor in any other manner except as indicated by the scope of the claims appended hereto.

What I claim is:

1. A concrete surfacing structure comprising a 15 base composed of straight-edged slabs, cooperating means secured to adjacent slabs and extending between the edges thereof to form interlocking expansion joints, recessed covers seated on said joints, straight-edged strips seated in the 20 recesses of and projecting above said covers, and slabs of concrete extending between and flush with the projecting edges of said strips.

2. A building construction comprising a wall 25 formed of spaced-apart studs, a plurality of straight-edged concrete slabs, metallic interlocking expansion joints extending between the edges of adjacent slabs, and means connected to said expansion joints for securing said slabs 30 to said studs.

3. A building construction comprising a wall 35 formed of spaced-apart studs, a plurality of straight-edged concrete slabs, metallic interlocking expansion joints extending between the edges of adjacent slabs, means connected to said expansion joints for securing said slabs to said studs, and a U-shaped cover embracing said expansion joints, said cover being flush with the surfaces of said slabs.
